(57) CLAIM

The ornamental design for a champagne cooler, as shown and described.

DESCRIPTION

FIG. 1 is a perspective view from slightly above the champagne cooler of the present invention.

FIG. 2 is a first side elevation view of the champagne cooler of FIG. 1.

FIG. 3 is a second side elevation view of the champagne cooler taken at a 90 degree azimuth angle to the view in FIG. 2

FIG. 4 is a top plan view of the champagne cooler of FIG. 1; and,

FIG. 5 is a bottom plan view of the champagne cooler of FIG. 1.
